ATTORNEY

UNITED STATES PATENT OFFICE.

MITCHELL L. FYKSE, OF MILWAUKEE, WISCONSIN, ASSIGNOR TO BUCYRUS COMPANY, OF SOUTH MILWAUKEE, WISCONSIN, A CORPORATION OF WISCONSIN.

REMOVABLE WHEEL.

Application filed July 21, 1922. Serial No. 576,603.

To all whom it may concern:

Be it known that I, MITCHELL L. FYKSE, a citizen of the United States, and a resident of Milwaukee, in the county of Milwaukee, and State of Wisconsin, have invented certain new and useful Improvements in Removable Wheels; and I do hereby declare that the following is a full, clear, and exact description thereof.

10 My invention relates to new and useful improvements in removable wheels, and has for its principal object to provide turntable rollers which can be easily removed.

15 I have particularly in mind turntable rollers for excavating machinery of the sort described in co-pending application; but it is evident that my invention is equally applicable to the rollers of any sort of turntable, or for that matter, to any wheel similarly situated, and of which the removal presents similar difficulties, or to any other wheel or rotating body.

20 A turntable usually consists of a circular track, resting on a lower frame, a pivot concentric with said track and disposed perpendicular to the plane thereof, and an upper frame revolving about said pivot and carrying rollers which rest on said track. In the case of the turntable of a self-propelled unit, the central pivot is usually hollow and contains the power shaft of the propelling machinery. The rollers frequently become worn or broken, and so have to be removed; for which purpose it is usually necessary 25 to jack up the entire upper frame, so that the rollers will be clear of the track. This method of removal necessitates having jacks available, the expenditure of a great amount of time, and having a man go inside the track between the two frames, for which small turntables do not provide sufficient room.

30 By the use of the within described invention, however, it is possible to remove any individual roller from the outside, within the duration of a very few minutes, and without jacking or other disturbance of the relative position of the other parts of the turntable.

Other advantages of the simple design of 50 my roller and its supporting means will naturally suggest themselves as the description progresses.

With these general objects in view, the invention resides in the novel features of 55 construction, combination and arrangement of parts which will be hereinafter more particularly described and claimed, and shown in the accompanying drawings, wherein:

Figure 1 is a vertical transverse sectional 60 view taken centrally through the vertical power shaft of the propelling machinery, and showing particularly the relative position of the circular track, the pivot, the upper frame and one of the rollers carried 65 thereby.

Figure 2 is a plan view of this roller and of the part of the upper frame carrying the same, taken from beneath.

Figure 3 is an enlargement of the sec- 70 tional view of the roller as shown in the Figure 1.

Figures 4 and 5 are elevation views of the roller-supports shown in Figure 3, these views being taken at right angles to the positions of Figure 3.

Referring more particularly to the drawings, and especially Figure 1, it will be seen that the vertical power shaft 1 carries on its upper end a bevel gear 2, which is driven by 80 the operating machinery (not shown), and on its lower end a bevel gear 3, which drives the propelling machinery (not shown). This power shaft is free to rotate in the pivot 4, which is an integral part of the 85 lower frame 5. The upper frame 6 is free to rotate about this pivot. The lower frame 5 carries a circular track 7 and a circular track 8, on which run the rollers 9.

Referring now more particularly to Fig- 90 ures 3 and 2, it will be seen that, with respect to each roller 9, there depend from the upper frame 6 two dissimilar brackets 10 and 11. Bracket 10 carries an ear 12, and rests on a bushing 13.

The roller 9 is free to rotate on the pin 14, one end of which rests in the bushing 13, and the other end of which rests in a

hole 15 in the bracket 11. The pin 14 is secured in place by a bolt 16 which passes successively through the bushing 13, the pin 14, the bushing 13 and the ear 12, and is secured by a cotter-pin 17. The conical shape of the roller 9, as it rests upon the track 8, forces it against the annular flange 18 of the bushing 13, against which it is free to rotate.

10 The method of removal of a roller 9 is as follows: The cotter pin 17, the bolt 16 and the pin 14 are successively withdrawn. The bushing 13 then easily slips down and out between the roller 9 and the bracket 10, leaving the roller free to take the position shown by the dotted lines in Figure 3, and hence to be removed. The assembling of these parts is as simple as the disassembling, the operations merely being reversed.

15 20 From the foregoing description, taken in connection with the accompanying drawings, it will be obvious that many changes may be made in the form and proportions of the different parts of the invention and 25 in the manner of assembling and disassembling the same, without departing from the principal features thereof as outlined in the appended claims.

It is also obvious that my invention is unchanged if the turntable be inverted so that the track runs on the rollers, or if it be put in any other position, since the novelty and utility of my invention lies in the features which render it easily removable.

30 35 I claim:

1. In a turntable, the combination of a revolving frame, a track, a plurality of rollers resting thereon and supporting said frame, said rollers being removable in a substantially axial direction, while said frame and said track are in normal relation to each other, and a bushing for each of said rollers, each bushing transmitting the end-thrust of its roller directly to said frame.

40 45 50 55 2. In a turntable, the combination of a revolving frame, a plurality of pivots supporting said frame, a track, a plurality of rollers resting on said track, each roller turning on one of said pivots, said rollers being removable in a substantially axial direction, while said frame and said track are in normal relation to each other, and a bushing for each of said rollers, each bushing transmitting the end-thrust of its roller directly to said frame.

60 65 70 75 80 85 90 95 100 105 110 115 120 125 130 3. In a turntable, the combination of a circular track, a pivot centrally disposed with respect to said track, and having its axis perpendicular to the plane thereof, a frame rotatably mounted on said pivot, a plurality of rollers carried thereby and running on said track, said rollers being removable while said frame and said track maintain their normal relative position, and a bushing for each of said rollers, each bushing

transmitting the end-thrust of its roller directly to said frame.

4. The combination of a turntable roller, a pin about which it rotates, a bushing disposed about one end of said pin and having an annular flange resting against one face of said roller, a bracket supported by said bushing and secured to said bushing and pin, another bracket supported by the other end of said pin, and a turntable supported by said two brackets.

5. The combination of a turntable roller, a pin about which it rotates, a bushing disposed about one end of said pin and having an annular flange resting against one face of said roller, a bracket supported by said bushing, removable securing means for securing said bracket to said bushing and said pin, another bracket supported by the other end of said pin, and a turntable supported by said two brackets, said parts being separable by the successive removal of the securing means, the pin, the bushing and the roller.

6. In a turntable, the combination of a revolving frame proper, a circular track, a plurality of rollers, resting on said track, an equal number of pins, each serving as the axle for one of said rollers, an equal number of bushings each disposed about one end of one of said pins and having an annular flange resting against one face of one of said rollers, an equal number of brackets each supported by one of said bushings and secured to said bushing and to one of said pins by removable means, and another equal number of brackets each supported by the other end of one of said pins, said two sets of brackets supporting the turntable proper, each roller being separable by the successive removal of the securing means, the pin, the bushing and the roller.

7. The combination of a wheel, a pin about which it rotates, a bushing disposed about one end of said pin and having an annular flange resting against one face of the hub of said wheel, a bracket supporting or supported by said bushing, removable means for securing said bracket to said bushing and pin, and another bracket supporting or supported by the other end of said pin, said two brackets thus supporting or being supported by said wheel proper, said parts being separable by the successive removal of the securing means, the pin, the bushing and the wheel.

8. The combination of a frame, a wheel, an axle about which it can rotate, unitary means for supporting one end of said axle and for preventing the wheel proper from sliding in one direction on said axle, means carried by said frame for supporting the other end of said axle, and means for securing together said first named supporting means, said axle and said frame.

9. The combination of a frame, a wheel, an axle about which it can rotate, means for supporting one end of said axle, and for preventing the wheel proper from sliding in one direction on said axle, means carried by said frame for supporting the other end of said axle, and means for securing to-

gether said first named supporting means, said axle and said frame, for supporting said first named supporting means, and for preventing said axle from sliding in the direction named. ¹⁰
